PLUG RETAINER

Herman Brugger, West Los Angeles, Calif.

Application July 24, 1935, Serial No. 32,897

9 Claims. (CL 247—23)

My invention relates to detachable electrical connectors used in electrical wiring systems, and relates in particular to that type of connector known as "plug and receptacle", the receptacle being ordinarily mounted in a wall or floor and having openings therein to receive contacts which project from a plug connected to the end of a cable or wire.

It is an object of the invention to provide a retaining means which will grip the body portion of the connector plug so as to hold it in operative position relative to the receptacle with such force or strength that the plug cannot be readily removed from such position of operation.

It is an object of the invention to provide a device of this general character which will grip plugs having bodies of different size. Electrical appliances generally come equipped with cords and plugs. These plugs, although having contacts of standard size and spacing so as to fit a standard size receptacle have bodies which vary in size and design in accordance with the personal likings of the designers. My invention has means for holding plug bodies of the various types found on the market and is effective so long as the sizes of the bodies are kept within reasonable limits.

It is an object of the invention to provide a retaining device having jaws for gripping or holding engagement with the surface of the plug body, and manually operable means for forcing these jaws into engagement with the plug body. The plugs used in standard housing wiring systems are intended to be held in place by the frictional engagement of the prongs or contacts of the plug with the contacts of the receptacle. Ordinarily, the engagement of these members becomes loose in a relatively short period of time so that often the weight of the electrical cord, or a relatively slight movement thereof, will remove the plug from the receptacle. In my device frictional engagement of the plug contacts with the receptacle contacts is not depended upon for holding the plug in position, nor are the contacts depended upon for this purpose. The gripping means employed in my device engage the body of the plug, or, in other words, that part of the plug from which the contacts project.

It is an object of the invention to provide a retaining device of the above character which may be secured to the face plate of a standard type of receptacle such as now commonly used and preferably without the need of screws other

than those furnished with the plate of the receptacle.

It is a further object of the invention to provide a device having few parts of simple form and having a cam of ring shape operating within an annular casing equipped with means for holding the gripping jaws in operative position.

Further objects and advantages of the invention will be made evident throughout the following part of the specification.

Referring to the drawing, which is for illustrative purposes only,

Fig. 1 is a partly sectioned face view of an electrical receptacle equipped with a preferred form of my invention.

Fig. 2 is a cross section on a plane indicated by the line 2—2 of Fig. 1.

Fig. 3 is a fragmentary cross section taken as indicated by the line 3—3 of Fig. 1.

Fig. 4 is a face view of the cam member employed in the device disclosed.

Fig. 5 is a cross section taken as indicated by the line 5—5 of Fig. 4.

Fig. 6 is a sectional view similar to Fig. 2, showing the jaws thereof in a position to grip a plug body.

In Figs. 1 and 2 I show a connector receptacle 10 of the type ordinarily employed in 110-volt electrical systems, such receptacle having slots 11 in the front thereof through which the prong-like contacts of a connector plug project into engagement with contacts, not shown, disposed within the body of the receptacle 10. Such receptacle 10 ordinarily has a face plate 12, and a pair of screws 13 are ordinarily provided for securing the face plate 12 and the receptacle 10 to the front of an outlet box forming part of an electrical distribution system.

My invention employs a supporting member 14 which is preferably stamped from relatively thin sheet metal and has a front annular wall 15 which lies in parallel relation to the front face of the face plate 12. This annular wall has an opening 16 therein larger than and concentric with the receptacle 10. The opening 16 is consequently a little larger than the diameter of the base of the largest standard plug. Extending inwardly or rearwardly from the peripheral edge 17 of the wall 15 is a flange or side wall 18, the inner edge 19 of which is adapted to rest against the outer face of the face plate 12. A pair of lugs 21 are extended radially from the supporting member 14 in such position that the securing screw 13 of the face plate 12 may be passed therethrough so that the screws 13 will serve the

double function of holding the retaining device on the face plate 12 and also holding the face plate on the front of the outlet box. Extending inwardly from the inner edge 19 of the side wall or flange 18, in diametrically opposed relation, are 5 a pair of lugs or tongues 22 having spaced loops or tubes 23 at the inner edges thereof for holding hinge pins 24 adapted to support jaw members 25 so that they will swing from the positions in 10 which they are shown in Fig. 2 to the positions in which they are shown in Fig. 6. Each of the jaw members 25 has a radially extending plate portion 26 and an end portion 27 bent so as to lie at substantially right angles to the radial portion 26, there being teeth 28 formed on the edge 15 of each portion 27 for engagement with the body 29 of a connector plug 30 such as shown in Fig. 6. Over each of the jaw members 25 the front annular wall 15 of the container is pressed outwardly 20 to form an enlargement or canopy 32 giving space into which the jaw members 25 may swing in retracted position as shown in Fig. 2. The walls 15 and 18 of the supporting member 14 define an annular space 33 adjacent the front face of the face plate 12, and in this annular space 33 a ring 25 34 is disposed which has an operating handle 35 projecting radially outwardly through a slot 36 in the cylindrical wall 18 so as to provide a limited rotation of the ring 34 around the axis 30 A—A of the receptacle 10. This ring 34 has cams 37 formed in diametrically opposed relation for engaging and swinging the jaw members 25 inwardly from retracted position, as shown in Fig. 2, to extended or gripping position, as shown in 35 Fig. 6. Each cam 37 has a cam face 38 which progresses spirally inwardly toward the center of rotation but at the same time twists on an axis parallel to the front face of the plate 12 so that each cam face 38 will follow the change in 40 position of the radial wall 26 of a jaw member 25 as the jaw member is swung inwardly from the position in which it is shown in Fig. 2 to its position of Fig. 6. Accordingly, the low or large 45 diameter portion 40 of each cam face 38 slopes upwardly and outwardly as indicated in Fig. 2. At this time the jaw member 25 rests against the portion 40 of the cam face in outwardly sloping position. The high or small diameter portion 41 of the cam face 38 slopes upwardly and inwardly so that as the ring 34 is rotated in clockwise direction to bring the high part 41 of the 50 cam face 38 into engagement with the jaw member 25, such jaw member 25 will be rotated into an inwardly sloping position as shown in Fig. 6. Between the outwardly sloping face portion 38 55 and the inwardly sloping face portion 41, each cam has an intermediate face portion 42 parallel to the axis A—A. It will be perceived that the twist of the cam face 38 corresponds to or follows 60 the change in position of the radial wall 26 of each jaw member 25 as the jaw members 25 are swung inwardly by the action of the cams 37. A simple spring member 44 yieldably urges the 65 jaw members 25 outwardly toward their retracted positions.

When the handle 35 is in the position in which it is shown in Figs. 1 and 4, the low portions 40 of the cam faces 38 will be in engagement with the portions 26 of the jaw members 25 so that the 70 spring 44 may hold the jaw members in retracted position as shown in Figs. 1 and 2. At this time a connector plug, such as the plug 30 shown in Fig. 6, may be caused to engage the receptacle 10; that is, the prongs of the plug may 75 be passed into the openings 11, and the body of

the plug may be brought to rest against the exposed face of the receptacle 10. The body 29 of the plug will then lie within the opening 16 of the supporting member 14, and the jaw members 25 may be swung inwardly by rotating the handle 35 and the ring 34 in clockwise direction, thereby causing the jaw members 25 to engage the body 29 of the plug 30 as shown in Fig. 6.

Connector plugs are ordinarily made from composition insulating material, for example, hard 10 rubber compounds, resilient rubber compounds, bakelite, and moldable compounds of fibrous material and suitable binders and fillers. The jaw members 25 may have the teeth 28 thereof of such hardness that they will readily grip materials of 15 this character so as to hold the plugs in place against relatively heavy forces tending to remove the same. It may not be advisable, however, to grip a connector plug with such tightness that the wire would be broken before the plug could 20 be pulled from place.

Although I have herein shown my invention in simple and practical form, it is recognized that certain parts or elements thereof are representative of other parts, elements, or mechanisms 25 which may be used in substantially the same manner to accomplish substantially the same results; therefore, it is to be understood that the invention is not to be limited to the details disclosed herein but is to be accorded the full scope 30 of the following claims.

I claim as my invention:

1. In combination with an electrical receptacle adapted to receive a plug, a holding means of the character described, comprising: jaw means 35 disposed in spaced relation to the front of said receptacle and being adapted to engage the body of a plug so as to hold the same in engagement with said receptacle; and a ring-like cam member adapted to be rotated so as to move said jaw 40 means to and from engagement with said body of said plug.

2. In combination with an electrical receptacle adapted to receive a plug, a holding means of the character described, comprising: jaw means 45 disposed in spaced relation to the front of said receptacle and being adapted to engage the body of a plug so as to hold the same in engagement with said receptacle; and a ring-like cam member adapted for rotation to move said jaw means 50 into engagement with said body of said plug.

3. In combination with an electrical receptacle adapted to receive a plug, a holding means of the character described, comprising: a pair of jaw members adapted to move radially inwardly 55 into engagement with the body of a plug so as to hold the same in engagement with said receptacle; and a ring-like cam disposed around the axis of said plug and adapted to be rotated about said axis, said cam having faces engaging said jaw members and forcing them inwardly into holding engagement with said body as said cam is rotated.

4. In combination with an electrical receptacle adapted to receive a plug, a holding means of the 65 character described, comprising: a pair of jaw members adapted to move radially inwardly into engagement with the body of a plug so as to hold the same in engagement with said receptacle; and a ring-like member disposed around the axis of 70 said plug and being rotatable around said axis, there being means operative through rotation of said ring-like member to move said jaw members into clamping engagement with said body of said plug.

5. In combination with an electrical receptacle adapted to receive a plug, a holding means of the character described, comprising: a supporting member adapted to be secured to the face plate 5 of said receptacle; jaw members movably mounted on said supporting member so as to be moved into engagement with the body of a plug engaging said receptacle; and ring-like means carried by said supporting member and adapted for rotation around the axis of said plug so as to move said jaw members into holding engagement with said body of said plug.

6. In combination with an electrical receptacle adapted to receive a plug, a holding means of the 15 character described, comprising: a supporting member adapted to be secured to the face plate of said receptacle; jaw members movably mounted on said supporting member so as to be moved into engagement with the body of a plug engaging said 20 receptacle; a ring carried by said supporting member in a position around the axis of said body; a handle projecting from said ring whereby it may be given rotary movement; and cams formed on said ring in positions to force said jaw 25 members into engagement with said body as the ring is rotated.

7. In combination with an electrical receptacle adapted to receive a plug, a holding means of the 30 character described, comprising: a supporting member adapted to be secured to the face plate of said receptacle; jaw members movably mounted on said supporting member so as to swing on axes substantially parallel to the front surface of said 35 face plate into engagement with the body of a plug engaging said receptacle; a ring carried by said supporting member in a position around the axis of said body; a handle projecting from said ring whereby it may be given rotary movement; and cams formed on said ring in positions to 40 force said jaw members into engagement with said body as the ring is rotated.

8. In combination with an electrical receptacle adapted to receive a plug, a holding means of

the character described, comprising: a supporting member adapted to be secured to the face plate of said receptacle; jaw members movably mounted on said supporting member so as to swing on axes substantially parallel to the front surface 5 of said face plate into engagement with the body of a plug engaging said receptacle; a ring carried by said supporting member in a position around the axis of said body; a handle 10 projecting from said ring whereby it may be given rotary movement; cams formed on said ring in positions to force said jaw members into engagement with said body as the ring is rotated; and spring means engaging said jaw members so as to urge them away from said body. 15

9. In combination with an electrical receptacle adapted to receive a plug, a holding means of the character described, comprising: a supporting member adapted to be secured to the face plate of said receptacle, said supporting member comprising an annular wall of thin metal having a central opening of such size that the body of a plug may pass therethrough as said plug is moved into position to engage said receptacle, and said supporting member also including an annular flange around the outer edge of said annular wall, said annular wall and said flange forming an annular space adjacent the surface of said face plate; jaw members disposed on axes substantially parallel to said surface of said face plate so as to swing into engagement with said body of said plug to grip the same; a ring disposed in said annular space formed by said supporting member so as to have a limited rotation around the axis of said opening; a handle projecting in radial direction from said ring whereby the same may be rotated; and cams formed on the inner portion of said ring so as to engage said jaw members and swing the same inwardly, there being yieldable means tending to swing said jaw members 20 25 30 35 40 outwardly.

HERMAN BRUGGER.
